UNITED STATES PATENT OFFICE

ARNOLD R. BINGGELI, OF KANSAS CITY, MISSOURI

ARTICLE DISPENSER

Application filed April 7, 1930. Serial No. 442,269.

My invention relates to improvements in article dispensers. It is particularly well adapted for dispensing stick articles, such as cigars, cigarettes, stick candy and the like, but is not restricted to the dispensing of such shaped articles.

One of the objects of my invention is to provide a dispenser of the kind described with novel means by which articles held in a receptacle may be discharged therefrom one at a time without injury thereto, and without liability of the articles clogging the outlet of the receptacle or of becoming turned cross-wise in the receptacle.

15 A further object of my invention is to provide a dispenser of the kind described, which is simple, cheap, strong, durable, not likely to get out of order, which is easy to operate, and which is reliable in its operation.

20 The novel features of my invention are hereinafter fully described and claimed.

In the accompanying drawing, which illustrates the preferred embodiment of my invention,

25 Fig. 1 is a side elevation of my improved article dispenser, with one side removed, the lid closed, and the article supporting and ejecting members shown, in solid lines, in their initial positions, cigarettes being shown 30 in the receptacle.

Fig. 2 is a view similar to Fig. 1, showing the supporting and ejecting members in the delivery positions, and a delivered cigarette resting on the external support therefor.

35 Fig. 3 is a perspective view of my improved dispenser, showing the lid raised.

Fig. 4 is a reduced plan view of the lever. Similar reference characters designate similar parts in the different views.

40 The receptacle for holding the articles to be dispensed therefrom comprises a boxlike body 1 having a top filling opening 2 adapted to be normally closed by a hinged lid 3.

The front of the body 1 has a horizontal slot 4 which forms an outlet for the dispensed articles, such as cigarettes 5.

Hinged at its rear edge to and in the body 1 is a flat article supporting member 6 which inclines forwardly and downwardly toward 50 the outlet 4.

7 designates a horizontal transverse ejecting member having an outwardly and downwardly inclined upper edge, and disposed between the outlet 4 and the front edge of the supporting member 6. The lower edge of 55 the ejecting member 7 is pivotally mounted on the upper side of the forward end of a lever 8, which consists of a plate having a transverse U-shaped channel portion 9 the under side of which rests pivotally on the 60 upper side of the bottom of the body 1. Two pins 10 extend through and are respectively loosely fitted in two holes 11 in the bottom of the channel portion 9, said pins being mounted in the bottom of the body 1 and serving 65 to retain the lever 8 in its operative location.

An operating vertical plunger 12 is vertically reciprocative in a hole provided in the top of the body 1 at the rear of the filling 70 opening 2. The upper end of the plunger has on it a thumb button 13. The lower end of the plunger 12 is disposed between and pivoted by a horizontal pin 14 to two ears 15 with which the lever 8, at the rear of the channel 75 portion 9, is provided.

The downward swinging of the supporting member 6 is limited by a cleat 16 fastened to the inner side of one side of the body 1.

For swinging upwardly the supporting member 6, the rear side of the ejecting member 7 has fastened to it a longitudinal cleat 17, which, when the ejecting member 7 is raised to the position shown in dotted lines in Fig. 1, engages the under side of the supporting member 6 and swings the latter upwardly on the continued upward movement of the ejecting member 7 to the position 90 shown in Fig. 2.

The articles, such as cigarettes 5, to be dispensed are piled transversely in the receptacle body 1 upon the supporting member 6. The sloping upper sides of the supporting member 6 and ejecting member 7 causes the cigarettes to move downwardly by gravity until the foremost cigarette lies on the upper edge of the ejecting member 7 and against the inner side of the front of the 100

body 1 below the outlet 4, as shown in solid lines in Fig. 1.

When the button 13 and plunger 12 are depressed to the position shown in dotted lines 5 in Fig. 1, the lever 8 will be swung by the plunger 12 so as to lift the ejecting member 7 to the position shown in dotted lines in Fig. 1, thereby lifting the cigarette which is carried on the ejecting member 7, the latter 10 striking the next succeeding cigarette and forcing it rearwardly and preventing its forward movement.

Upon the continued upward movement of the ejecting member 7, the cigarette carried 15 thereby will be lifted above the bottom of the outlet 4, and the latter, being inclined forwardly and downwardly, the lifted cigarette will be delivered by gravity through the outlet 4, and will drop upon two supporting devices 18, fastened to the outer side 20 of the body 1 below the outlet 4, and provided each in its upper side with a recess 19 into which the dispensed cigarette is deposited and rests.

25 The body 1 is provided with means cooperating with the supporting member 6 and the ejecting member 7 for separating, during a dispensing operation, the foremost article to be dispensed from the one next succeeding it. Such separating means embodies wedging means consisting of a wedge shaped portion 20 with which the inner side of the front of the body 1, above the outlet 4, is provided. The wedge shaped portion 20 has its 30 lower sharp portion disposed in a vertical plane between the supporting member 6 and the ejecting member 7. The rear side of said wedge shaped portion 20 inclines upwardly and rearwardly, as designated by 21.

40 When in the upward movement of the ejecting member 7, the cleat 17 thereon lifts the front edge of the supporting member 6, the latter, in lifting the cigarettes carried thereon, will force the cigarette next succeeding the one on the ejecting member 7 against the slanting portion 21, whereby said 45 succeeding cigarette and the ones to the rear of it will be forced rearwardly and upwardly on the supporting member 6, as shown in Fig. 2.

50 In the meantime, the cigarette carried upwardly by the ejecting member 7 will be delivered through the outlet 4 onto the supporting devices 18, from which it can be removed at the pleasure of the operator.

Upon the operator releasing the button 13, the supporting member 6 and the ejecting member 7 will lower by gravity to the position shown in solid lines in Fig. 1, thereby 60 causing the lever 8 to be swung to lift the plunger 12 to its initial raised position, shown in solid lines in Fig. 1.

From the inclined portion 21, the inner side of the front of the body 1 preferably 65 inclines forwardly and upwardly, to enable

the articles carried by the supporting member 6 to be moved bodily upwardly without crowding or jamming, when the supporting member 6 is swung upwardly, as has been described.

As shown in Fig. 1, there is a lost motion between the actuating member 7 and the supporting member 6, by which the cigarette or other article 5 which is on top of the member 7 is carried upwardly prior to the lifting of the member 6, thus enabling the member 7 to get in front of and engage the cigarette next in the rear and hold it and the other cigarettes back before they have been lifted or moved forwardly. This effectually prevents jamming.

As shown, the front side of the wedge portion 20 inclines upwardly and forwardly, so that when a cigarette or other article 5 is lifted to a position in which it registers with the outlet 4 said inclined front side of the wedge engages the article at its rear side and positively forces it forwardly and downwardly, thus preventing a bent or otherwise deformed article from clogging the outlet.

While I have described my dispenser as being adapted for dispensing cigars, cigarettes and stick candy, it is obvious that, by making it in proper dimensions, it may be employed for dispensing other articles which will roll down an inclined surface, as cylindrical articles, such as pencils.

I do not limit my invention to the structure shown and described, as many modifications, within the scope of the appended claim, 100 may be made without departing from the spirit of my invention.

What I claim is:—

In an article dispenser, the combination of a receptacle having a body provided with an outlet in one side for articles to be dispensed, and having at the inner side of said side a wedge portion at the rear of said outlet, said wedge portion at its rear side inclining upwardly and rearwardly, and the inner side of said side of said body inclining upwardly and forwardly from said inclined part of said wedge portion, an article supporting member adapted to support articles to be dispensed and pivoted on a horizontal axis and inclining forwardly and downwardly toward said outlet and said wedge portion, an ejecting member vertically movable between said outlet and said supporting member from a position at the rear of and below said outlet, in which position it is adapted to receive thereon from said supporting member and lift to a delivery position at the rear of said outlet the foremost of said articles, and having means for engaging and swinging upwardly said supporting member after said ejecting member has moved upwardly in front of the next succeeding member, said wedge portion being so disposed as to enter between said foremost article and the article

next succeeding to engage and force the latter rearwardly and upwardly on said supporting member, when said supporting member and said ejecting member move upwardly,
5 and means for moving said ejecting member upwardly.

In testimony whereof I have signed my name to this specification.

ARNOLD R. BINGGELI.
